DESCRIPTION

FIG. 1 is a front, bottom and left side perspective view of a vacuum bottle stopper for wine showing my new design; FIG. 2 is a rear, top and left side perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1; and,

FIG. 8 is a bottom plan view of FIG. 1.

The broken lines in FIGS. 1-8 depict environmental structure. All broken lines form no part of the claimed design.
